UNITED STATES PATENT OFFICE.

RAFAEL MARTINEZ, OF NEW YORK, N. Y.

WINDOW.

SPECIFICATION forming part of Letters Patent No. 325,753, dated September 8, 1885.

Application filed June 29, 1885. (No model.)

To all whom it may concern

Be it known that I, RAFAEL MARTINEZ, a citizen of Spain, residing at New York, in the county of New York and State of New York, have invented certain new and useful Improvements in Windows, of which the following is a specification, reference being had therein to the accompanying drawing.

My invention relates to improvements in windows in which both the upper and lower sashes are counterbalanced by weights and are arranged to slide up and down in their frame; and the objects of my improvements are to provide means for hinging one side of the sashes to the frame and swinging them inwardly to facilitate the cleaning or washing of the panes thereof. I attain these objects by the construction illustrated in the accompanying drawing, in which a window-frame is represented having its lower sash elevated to the top of the frame and its top sash lowered and partly swung inwardly to show its side supports and the position the hinged parts occupy before the sash can be turned inwardly.

In the drawing, G represents a window-frame provided with vertical grooves G' for the sashes to run into, these grooves being between facing-strips B' and the parting-strip E'. These strips are permanently secured to the frame upon one side of the window-opening and extend the whole length thereof, and to them are secured the eyes or sockets F' of the sash-hinges, while projecting inwardly from the sashes are the pendent hinge hooks or pintles F, of suitable size to easily enter these sockets and form hinges with them. The sockets to receive the pintles of the lower sash, C, are projecting from the inner facing-strips, B', while the sockets to receive the pintles of the upper sash, D', are projecting from the parting-strip E'. The pintles of each sash are not quite perpendicularly one above the other; the lower pintle is farther from the edge of the sash or from the side strips of the frame, so that it will pass the upper hinge-socket and enter the lower one only; and these sockets are correspondingly projecting from the side strips of the frame. Upon one side of the frame the side

strips are cut in two about the middle of their length, and the inner facing-strips, B, are retained connected to the frame by means of hinges b, to permit one edge of the lower sash, C, to escape from its groove toward the interior of the room. The sill-strip A is preferably hinged also to the sill of the frame, so that to swing the sash D the inner sash, C, need not be pushed up quite so high, but yet on the under side of its top the frame G is recessed about one inch and a half deeper than usual to receive the upper edge of the sash C and allow the sash D to turn on its hinges without coming in contact with the bottom rail of the sash C. The lower end of the parting-strips E carries a screw-eye or button e, to secure it to the frame at that end, while the upper end is beveled to engage under the lower edge of the upper parting-strip. After the sash D has been turned inward as much as the sash weight and cord g will allow, the looped end of said cord is drawn out of its socket d in the side of the sash and temporarily fastened to the pin g', projecting from the face of the window-frame. The sash, thus freed from all impediments on one side, can be turned upon its hinges and its panes cleaned on both sides from within the room, and the danger to the operator thus removed. After one sash has been cleaned the looped end of the cord g is replaced in its socket d and the sash replaced in its frame. A similar operation is practiced upon the second sash, after which the parting-strip E is replaced and secured to the window-frame, the facing-strip B swung back to its normal position, as well as the sill-strip A.

Having now fully described my invention, I claim—

1. A window-frame having hinge-sockets F' on one side, permanently projecting from said frame, vertically-sliding sashes provided with sash-cords, and hinge-pintles projecting from the sashes to engage with said hinge-sockets, substantially as and for the purpose described.

2. The combination of a window-frame, its hinged strips B, and hinge-sockets F, secured to the vertical strips of said frame, with ver-

tically-sliding sashes and hinge-pintles projecting therefrom, substantially as and for the purpose described.

3. The combination of a window-frame, its 5 vertical hinged strip B, hinged sill-strip A, and hinge-sockets F, secured to the vertical strips of said frame, with vertically-sliding sashes capable of passing each other, and hinge-

pintles projecting therefrom, substantially as and for the purpose described.

In testimony whereof I affix my signature in presence of two witnesses.

RAFAEL MARTINEZ.
